UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

CUTTING AND FOLDING MACHINE.

1,263,837.

Specification of Letters Patent. Patented Apr. 23, 1918.

Application filed June 22, 1916. Serial No. 105,178.

To all whom it may concern:

Be it known that I, HOWARD M. BARBER, a citizen of the United States, and resident of Stonington, in the county of New London and State of Connecticut, have invented a new and useful Improvement in Cutting and Folding Machines, of which the following is a specification.

The object of my invention is to provide 10 certain improvements in cutting and folding machines whereby a plurality of superimposed narrow webs may be positively and accurately fed in absolute register through the sheet cutting mechanism to the folding mechanism, thereby permitting the sheet 15 cutting and folding mechanisms to be run at a much higher speed than would otherwise be possible were the webs not so positively and accurately fed.

20 My invention more specifically comprises two pairs of positively driven coacting endless belts, the belts being located beyond the sides of the webs and beyond the ends of the coacting members of both the cutting 25 and folding mechanisms, said belts having coacting bars which project inwardly from the belts in position to grasp between them the sides of the superimposed narrow webs, each pair of said bars having an interlocked 30 engagement.

A practical embodiment of my invention is represented in the accompanying drawings, in which,

Figure 1 represents the cutting and folding machine in side elevation,

Fig. 2 is a front view of the machine, and

Fig. 3 is a vertical section taken in the plane of the line A—A of Fig. 2, looking in the direction of the arrows.

40 I have shown three sets of rolls 1, 2, 3, 4, 5, 6, arranged to superimpose six narrow webs.

The cutting mechanism includes a pair of coacting rotary cutters 7, 8, carried by the 45 shafts 9, 10, mounted in the side frames of the machine. The folding mechanism includes the male folding cylinder 11 and the female folding cylinder 12, carried by their respective shafts 13, 14, mounted in the side 50 frames of the machine. The male folding cylinder 11 is shown as provided with two sets of grippers 15, 16, and two sets of folding blades 17, 18. The female folding cylinder 12 is shown as provided with two sets 55 of folding jaws 19, 20, arranged to coact

with the folding blades 17 and 18 respectively.

The sheet delivery mechanism is herein shown as comprising the endless tape carriers 21, 22, the guide 23, the rotary dropper 24, and the endless delivery carrier 25.

60 The cutting, folding and delivery mechanisms may be of any well known or approved form.

The means for positively feeding the superimposed narrow webs through the cutting mechanism to the folding mechanism is as follows:

Two pairs of coacting endless belts 26, 27, and 28, 29, are provided, which belts are 65 located entirely beyond the sides of the superimposed narrow webs and beyond the ends of the cutter knives and the ends of the blades and jaws of the folding mechanism. The upper ends of the belts 26 and 28 pass around the drum 30, and the lower ends of said belts pass around the male folding cylinder 11. The upper ends of the endless belts 27 and 29 pass around the drum 31, and the lower ends of said belts pass 70 around sprocket wheels 32, 33. Each pair of coacting belts 26, 27, and 28, 29, is provided with pairs of coacting bars 34, 35 and 36, 37 respectively, which bars project inwardly from the endless belts in position to 75 grasp between them the sides of the superimposed narrow webs. These pairs of inwardly projecting bars are equally spaced apart along the endless belts and act as teeth 80 for engaging recesses 38, 39, and 40, 41, in 85 the peripheries of the drums 30, 31 respectively, and recesses 42, 43, and 44, 45, in the peripheries of the male folding cylinder 11, and sprocket wheels 32, 33, for insuring 90 the positive driving of these belts. Each 95 pair of coacting inwardly projecting bars is also provided, the one member of a pair with a pin 46, and the other member with a recess for receiving the pin, to cause each pair of belts to have an interlocking driving engagement.

100 The sprocket wheels 32, 33, are so arranged with respect to the male folding cylinder 11, that the pairs of endless belts will travel together from the drums 30, 31, downwardly past the rotary cutters 7, 8, to the folding cylinder 11, and from thence a short distance along the periphery of the folding cylinder before the belts are permitted to separate. This causes the grippers 15, 16, on 110

the male folding cylinder 11 to have ample time to close gently upon the advance edge of the superimposed narrow webs while the webs are still being held in register on the 5 periphery of the folding cylinder, thus permitting the mechanism to be run at a much higher speed than would otherwise be possible.

Gearing 47, 48, 49, 50, 51, 52, 53, 54, 55, 56, 10 57, 58, 59, 60, 61, 62, 63, 64, 65, 66, provide means for driving the several mechanisms at the proper relative speeds. Guides 67, 68, are also provided for guiding the superimposed narrow webs from the cutting mechanism 15 to the folding mechanism.

In operation, the narrow webs which pass over the rolls 1, 2, 3, 4, and 5, 6, are superimposed and pass between the drums 30, 31, and are engaged at this point along their 20 sides by the pairs of coacting bars projecting inwardly from the endless belts. These bars firmly grasp the superimposed webs and the belts convey the webs through the cutting mechanism, as hereinbefore described, where 25 the advance edge of the webs, while still held in register by the bars, are engaged by either the set of grippers 15, or the set of grippers 16.

At about the same time the grippers engage 30 the webs, the cutting mechanism operates to sever the same and the sheets are then carried around the periphery of the cylinder 11, until the folding mechanism of the cylinders 11 and 12 coacts to fold off the 35 sheets to the cylinder 12, from which cylinder 12 the folded sheets are delivered by the tape carriers 21, 22, guide 23, and sheet dropper 24, on to the endless delivery carrier 25. Thus it will be seen that the superimposed 40 narrow webs may be positively fed through the cutting mechanism to the folding mechanism in accurate register and held in such register a sufficient time on the male cylinder to permit the easy operation of the grippers.

Claims on the cutting mechanism form the 45 subject-matter of a divisional application filed by me August 16, 1916, Serial Number 115,241, the claims in this present application being directed to the cutting and folding mechanism.

It is evident that slight changes may be resorted to in the form, construction and arrangement of the several parts without departing from the spirit and scope of my invention; and hence I do not wish to limit myself strictly to the structure herein shown and described, but

What I claim is:

1. In a machine of the character described, 60 a cutting mechanism, a folding mechanism and means for positively feeding a group of superimposed webs therethrough, comprising two pairs of endless belts located beyond the sides of the webs and beyond the operative parts of the cutting and folding mecha-

nisms, said belts being provided with devices for engaging the sides of the webs.

2. In a machine of the character described, a cutting mechanism, a folding mechanism and means for positively feeding a group of 70 superimposed webs therethrough, comprising two pairs of endless belts located beyond the sides of the webs and beyond the operative parts of the cutting and folding mechanisms, said belts being provided with interlocking devices for engaging the sides of the webs. 75

3. In a machine of the character described, a cutting mechanism, a folding mechanism and means for positively feeding 80 a group of superimposed webs therethrough, comprising two pairs of endless belts located beyond the sides of the webs and beyond the operative parts of the cutting and folding mechanisms, said belts being provided with 85 pairs of coacting devices for engaging the sides of the webs.

4. In a machine of the character described, a cutting mechanism, a folding mechanism and means for positively feeding a group of 90 superimposed webs therethrough, comprising two pairs of endless belts located beyond the sides of the webs and beyond the operative parts of the cutting and folding mechanisms, said belts being provided with pairs 95 of coacting interlocking devices for engaging the sides of the webs.

5. In a machine of the character described, a cutting mechanism, a folding mechanism and means for positively feeding a group of 100 superimposed webs therethrough, comprising two pairs of endless belts located beyond the sides of the webs and beyond the operative parts of the cutting and folding mechanisms, said belts being provided at regular 105 intervals with pairs of coacting devices for engaging the sides of the webs and means engaging the said devices for positively driving the belts.

6. In a machine of the character described, 110 a cutting mechanism, a folding mechanism and means for positively feeding a group of superimposed webs therethrough, comprising two pairs of endless belts located beyond the sides of the webs and beyond the operative parts of the cutting and folding mechanisms, said belts being provided at regular 115 intervals with pairs of coacting interlocking devices for engaging the sides of the webs and means engaging said devices for positively driving the belts. 120

7. In a machine of the character described, a cutting mechanism, a folding mechanism and means for positively feeding a group of superimposed webs therethrough, comprising two pairs of endless belts located beyond the sides of the webs and beyond the operative parts of the cutting and folding mechanisms, said belts being provided with 125 pairs of coacting inwardly projecting bars 130

arranged to grasp the sides of the webs between them.

8. In a machine of the character described, a cutting mechanism, a folding mechanism and means for positively feeding a group of superimposed webs therethrough, comprising two pairs of endless belts located beyond the sides of the webs and beyond the operative parts of the cutting and folding mechanisms, said belts being provided with pairs of coacting interlocking inwardly projecting bars arranged to grasp the sides of the webs between them.

9. In a machine of the character described, a cutting mechanism, a folding mechanism and means for positively feeding a group of superimposed webs therethrough, comprising two pairs of endless belts located beyond the sides of the webs and beyond the operative parts of the cutting and folding mechanisms, said belts being provided at regular

intervals with pairs of coacting inwardly projecting bars arranged to grasp the sides of the webs between them and means engaging said bars for positively driving the belts. 25

10. In a machine of the character described, a cutting mechanism, a folding mechanism and means for positively feeding a group of superimposed webs therethrough, comprising two pairs of endless belts located 30 beyond the sides of the webs and beyond the operative parts of the cutting and folding mechanisms, said belts being provided at regular intervals with pairs of coacting interlocking inwardly projecting bars ar- 35 ranged to grasp the sides of the webs between them and means engaging said bars for positively driving the belts.

In testimony that I claim the foregoing as my invention I have signed my name this 40
20th day of June, A. D. 1916.

HOWARD M. BARBER.
